UNITED STATES PATENT OFFICE.

CLARENCE E. HULL, OF SANTA BARBARA, CALIFORNIA.

INTERNAL-COMBUSTION ENGINE.

Application filed September 18, 1919. Serial No. 824,491.

To all whom it may concern:

Be it known that I, CLARENCE E. HULL, a citizen of the United States, and a resident of Santa Barbara, in the county of Santa Barbara and State of California, have made new and useful Improvements in Internal-Combustion Engines, of which the following is a specification.

My invention relates to improvements in internal combustion engines, and it consists in the constructions, combinations and arrangements herein described and claimed.

The foremost object of my invention is to provide an improved design of internal combustion engine, wherein simplicity of construction, and ease of assembling and disassembling are salient features.

Another object of the invention, properly designated under the above heading, is to provide an internal combustion engine having a valve-in-the-head arrangement with the cam shafts in the crank case, this particular arrangement, as more fully appears below, enabling the removal of the cylinder head for valve repair and regrinding operations, without endangering the original proper timing of the cam shafts.

A further object of the invention is to provide a novel arrangement in the ports and manifolds, this arrangement including a novel water jacketing structure, described below.

Other objects and advantages will appear in the following specification, reference being had to the accompanying drawings, in which:—

Figure 1 is a side elevation of the engine, parts being shown in section,

Figure 2 is a plan view of the engine, parts being shown in section,

Figure 3 is an enlarged detail sectional view, showing certain of the cylinder head parts more clearly, and

Figure 4 is a detail horizontal section taken substantially on the line 4—4 of Figure 3, and showing the arrangement of the water-jacketed dual valves,

As stated above, in designing this internal combustion engine, the foremost object in mind was to provide an engine of comparatively light weight without sacrificing any strength in the construction, the arrangement being such that the various important parts could be easily disassembled for the purpose of making inspections and repairs. Special constructions are employed

throughout the engine in order to make the attainment of the principal objects possible, and in order that these various constructions will be easily understood, such parts as relate to the present application are described in order.

The construction of the cylinders and head is clearly seen in Figures 1 and 3. The cylinders 3, of which there is any desired number, are cast en bloc and provided with flanges 28 by means of which the cylinder structure is secured to the channel iron 1 of the crank case structure, through the bolts 29. The hollow head 30 of the engine is removable so that all of the valves 26, 27 can be readily gotten at for convenience of making repairs and grinding the valves and seats.

A water jacket 31, cast integrally with the cylinders 3, envelops the upper ends of the cylinders as clearly shown in Figure 3 being continued in the removable head 30 through suitably disposed openings 32, which match when the head 30 is applied and fastened to the top of the cylinder structure. The intake ports 33 and exhaust ports 34 are as nearly surrounded by water as the construction will permit. Similarly, the intake manifold 35 is wholly surrounded by water, by reason of the fact that it is cast inside of the water jacket seat as clearly shown in Figure 3. Only the exhaust manifold 36 is exposed on the outside, any type of carburetor being applied directly to a suitable opening 38 on the intake side.

Bosses or guides 39, 40 protect the tappets 24 and 25 from the water in the water jacket 31, and also the gases where the tappets run through the top of the cylinder structure. These tappets actuate the valve arms 41, 42 which are suitably pivoted at 43, and are provided with double ends or fingers for moving both associated valves at the same time. It will be observed that the upper end of each cylinder is enlarged as at 44, to make room for the various valves as they open.

A spark plug 45 is centrally located with respect to the four companion valve openings, as clearly indicated in Figure 1. Each valve opening merges into a common port, which in turn communicates with a duct of the companion manifold, of the same shape. For example, the intake valve openings 46 merge into a common oval-shaped port 47, this port in turn communicating with the

oval-shaped duct 48 which leads to the intake manifold 35. The same structure is present on the other side of the engine, the exception being that in the case of the exhaust port 49, they merge into arcuate passages 50 which terminate on the outer wall of the water jacket 31 and in turn communicate with the exhaust manifold 36 when that member is bolted in place thereover.

10 The arrangement of the valve openings and ports just described, provides a wedge-shaped water passage 52 between the valves, which enables water to circulate almost completely around the whole valve structure. 15 It can be plainly seen particularly from Figure 3, that the various valves are normally held to their seats by means of springs 53, the valve stems proper working in bushings 54 which are suitably set in apertures 20 in the head 30.

Located at the longitudinal extremities of the cylinder structure are end webs 55, which are preferably cast as a part of the cylinder structure, and provided with flanges by means of which additional points of attachment to the channel iron 1 are provided. These end webs 55 assist in stabilizing the engine structure, and when the upper side plates or closures 56 are bolted 25 in place, the upper part of the engine presents a substantially rectangular configuration. The cam shafts 11 and the gears 57 which revolves them from a driving gear 58 on the crank shaft 18, are concealed by the 30 curved closure plates 59 which extend from the closure plates 56 to points of attachment on the T-shaped angle irons 15. A deep cover 60 encloses the valve actuating mechanism and cylinder head 30.

40 The advantages of the engine head structure in the foregoing description will now become apparent.

The valve structure can be completely removed without disturbing the cam shafts at 45 all. The head 30 is removable without disturbing the intake or exhaust ports and manifolds. In many modern engines it becomes necessary to remove either the exhaust or intake manifold, before the valve structure can be reached for repairs. There is 50 therefore a peculiar combination between the removable head 30 and the particular type of shaft hanger disclosed, even though these parts are relatively far removed from 55 each other, because the particular structure of one so cooperates with the other that the ultimate desirable result of easy accessibility is reached.

60 It is to be observed that but little stress is laid on the peculiar crank case construction, partially disclosed in Figure 2, this being for the reason that that construction is more fully disclosed in a co-pending patent application which was divided from the 65 present application. It has just been said

that there is a peculiar combination between the removable head and the particular type of shaft hanger in the crank case. This is so because the shaft hangers are of such construction that the cam shaft 11 can be 70 taken off without disturbing the head structure, and similarly, the head can be taken off with all of its carried parts, without disturbing the position of either cam shaft.

75 While the construction and arrangement of the improved internal combustion engine as herein described and claimed, is that of a generally preferred form, obviously modifications and changes may be made without departing from the spirit of the invention or 80 the scope of the claims.

I claim:—

1. An internal combustion engine including a multiple cylinder body having a water jacket, a tubular intake manifold lying 85 wholly within the water jacket and having a port communicating with the exterior of the body and a plurality of ports communicating with the top thereof, exhaust passages located within the water jacket of the 90 body at the side thereof opposite the intake manifold, said exhaust ports communicating with the exterior of the body and also with the top thereof, and a detachable valve carrying head having intake and exhaust 95 passages registering with the ports of the intake manifold and also with the ports of the exhaust passages in the top of the said cylinder body.

2. An internal combustion engine of the 100 class described including a cylinder body having a water jacket, an intake manifold pipe lying wholly within the water jacket and having a carburetor port communicating with the side of the body and a plurality 105 of outlets at the top of the body, exhaust passages formed in the body opposite the intake manifold and opening through the top and sides of said body, a detachable head carrying therewith intake and exhaust 110 valve units for each cylinder and having substantially inverted U-shaped passages for establishing communication between the outlets of the intake manifold and the intake 115 valves and also between the openings of the exhaust passages and the exhaust valves, and an exhaust manifold carried by the cylinder body.

3. An internal combustion engine including a cylinder bloc and a water jacket structure, an intake manifold pipe lying wholly within the water jacket at one side of the cylinders and having passages opening through the top of the bloc and a single carburetor port at the side, exhaust passages 120 also formed in the jacket and opening at the top and side of the bloc, and a detachable valve carrying head having passages registering with and establishing communication 125 respectively between the intake manifold 130

and the cylinders and between the exhaust passages and the cylinders.

4. An internal combustion engine including a multiple cylinder body having a water jacket, an intake manifold pipe lying wholly within the water jacket at one side of the cylinders, and having an inlet and outlet ports in the body, exhaust passages for each cylinder formed in the water jacket opposite the intake manifold, and communicating with the top and sides of the cylinder bloc, a detachable valve carrying head having means for establishing communication between the intake manifold and the exhaust passages and the cylinders, and an exterior exhaust pipe carried by the body below the plane of the top surface thereof and communicating with said exhaust passages.

CLARENCE E. HULL.
